UNITED STATES PATENT OFFICE.

GIOVANNI C. MAZZERI, OF VIRDEN, ILLINOIS.

REED-PROTECTING DEVICE.

1,376,213.

Specification of Letters Patent. Patented Apr. 26, 1921.

Application filed February 2, 1918. Serial No. 215,094.

To all whom it may concern:

Be it known that I, GIOVANNI C. MAZZERI, citizen of Italy, residing at Virden, in the county of Macoupin and State of Illinois, 5 have invented new and useful Improvements in Reed-Protecting Devices, of which the following is a specification.

This invention relates to protecting and adjusting devices for the reeds of musical instruments and one object is to provide a device by means of which the usual reed of a clarinet or other similar musical instrument may be regulated, for varying the effective length thereof, for purposes well known.

A further object is to provide a protecting device for a reed which will prevent the saliva from passing under the reed and causing injury to the latter.

With the foregoing and other objects in view, the invention consists in the construction, combination and arrangement of elements hereinafter described and claimed.

In the drawings,

Figure 1 is a view showing the reed in longitudinal section, with the protecting plate located below the reed.

Fig. 2 is a plan view of the plate.

Fig. 3 is a plan view of the reed.

Fig. 4 is a transverse section of the reed with the plate associated therewith.

Fig. 5 is a detail on an enlarged scale of a portion of the structure of Fig. 1.

In carrying out my invention, I provide in connection with the usual reed 10 mounted upon the mouthpiece of the instrument 12, a protecting plate, constituting also a regulating and adjusting member, this element last-named being designated 14. The main portion of the plate comprises a strip of metal, substantially rectangular in form and provided along oppositely located sides

and adjacent to one end with upwardly extending flanges 15 and 16 engaging the edge portions of the reed 10 and having frictional contact therewith.

A plurality of graduations are provided as shown at 18 in order that the individual playing the instrument may adjust the device 14 for varying the effective length of the reed when a soft, medium or loud note is desired.

All types of reeds found on the market absorb the saliva to such an extent that their vibratory qualities are seriously affected, and it is not possible to reach the high notes. The present device not only protects the reed from excessive moisture but stiffens it and permits of variation in the length, or rather in the effective length, in the manner indicated. It is possible to secure a number of variations in tone or volume without employing different reeds, as is customary under ordinary conditions. The reed is maintained in good condition no matter how long the instrument is in use at a given time, and the player finds it easy to make all notes clear and strong, and to reach B flat without difficulty. The article will be made of German silver, pure silver or gold.

What I claim is:

In a device of the class described, the combination with the body of a wind instrument and a reed carried thereby, of a plate extending longitudinally of the reed and between the latter and the mouthpiece of the instrument, said plate having upwardly extending flanges engaging the edges of the reed, and having frictional contact therewith permitting of adjustment with reference to the free end of the reed.

In testimony whereof I affix my signature.

GIOVANNI C. MAZZERI.
